(57) **CLAIM**

The ornamental design for a candle stand, as shown.

DESCRIPTION

FIG. 1 is a perspective view of the ornamental design of the candle stand showing our new design. The broken lines show the environment and do not form a part of the design of the claimed invention.

FIG. 2 is a side view of the candle stand, the opposite side thereof being identical thereto;

FIG. 3 is a end view of the candle stand, the opposite end thereof being identical thereto;

FIG. 4 is a top view of the candle stand; and,

FIG. 5 is a bottom view of the candle stand.
